SHUTTLE CHECKING DEVICE FOR LOOMS

Adolphe Zarn, Zurich, Switzerland

Application November 20, 1946, Serial No. 710,965
In Switzerland November 21, 1945

1 Claim. (Cl. 139—166)

1

The hitherto known shuttle checking devices present various and to some extent serious drawbacks. Thus, in the first place, the braking force of these devices must be exactly adjusted in order that the shuttle should come to a stop at the correct position on the loom batten. Since, however, the shuttle, in consequence of variations in the working conditions, such as wear, temperature and the effect of dirt, is not always braked with the same effect by the checking device, the known devices must be continuously adjusted by the master weaver. But even with the most careful attention, interruptions in working cannot be avoided since as soon as the shuttle does not come to rest exactly at the proper place, this can lead to the stoppage of the loom or in the case of automatic looms to faulty operation. If the shuttle tends to rebound, the operation of the bobbin is endangered.

In order to avoid these defects of the known shuttle checking devices, it has already been proposed to use a liquid buffer in combination with the usual brake tongue, in which the buffer or cushion is constructed as a liquid displacing body which has the tendency to return automatically to its normal position after the back stroke, the space out of which the member forces the liquid being in connection by at least one throttling conduit with a space filled with liquid.

By means of this known device, a considerable advantage has already been attained, the liquid buffer having the property of always adjusting itself automatically to the necessary braking force. But even this construction met with difficulties of a structural character.

Naturally, the requirements of a tight joint, with respect to efficiency and freedom from friction are so high that the usual means are insufficient. A particular difficulty consists in that whilst in working no liquid can pass out through the jointing, by the reciprocating motion of the piston small quantities of air are conveyed into the housing and there form, in time, an air cushion so that finally the moved buffer no longer conveys the liquid or exclusively liquid but liquid with air. But naturally, in order to ensure that the efficiency of the buffer remains intact, care must be taken that only liquid and not air can penetrate behind the piston.

An object of the present invention is a particular construction of a buffer of the liquid displacement type, in a shuttle checking device for looms, by which the drawbacks of the known constructions of this kind are avoided. According to the invention, this is attained by the pro-

5 vision above the piston packing which is constructed as a collar, and in the pump housing, of at least one valve for the passage of air. In this manner air forced into the housing by the movement of the piston at once escapes through a valve into the air space of the housing and cannot get behind the piston. There is furthermore preferably provided on the housing an inlet and excess pressure valve by which, in the first place, any possible excess pressure in the housing is avoided and, on the other hand air can be introduced. In order to attain an absolute separation of the air and liquid, the pressure cylinder is connected by an intermediate conduit with the lower portion of the housing so that air can never pass out of the air space into the pressure cylinder. Finally, as an alternative and in order not to weaken the cylinder walls with an opening, the cylinder wall may be so constructed that it surrounds the piston with a clearance. The outflow of the liquid is thereby automatically throttled and the provision of a separate throttling conduit is unnecessary.

20 On the annexed drawing, various embodiments 25 of the object of the invention are shown by way of example in Figs. 1 to 9.

Fig. 1 is a view of a shuttle checking device mounted on the end of a loom batten.

25 Fig. 2 is a plan view of the shuttle checking device according to Fig. 1.

Fig. 3 is a front view of a shuttle checking device according to Fig. 1.

30 Fig. 4 is a vertical section through a shuttle checking device on an enlarged scale.

Fig. 5 is a cross section on the line V—V of Fig. 4.

35 Fig. 6 is a section according to Fig. 5 with a supplementary arrangement.

Fig. 7 shows a combined inlet and excess 40 pressure valve on an enlarged scale.

Fig. 8 is a section on an enlarged scale 45 illustrating a second embodiment of a shuttle checking device.

Fig. 9 is a section on the line IX—IX of Fig. 8.

The end 1 of a loom batten shows in known manner a brake tongue 2. 3 indicates the picker on which the shuttle 4 strikes. On the loom batten 1 is mounted the checking device housing 5, the buffer head 6 of which rests on the picker 3. As can be seen from Fig. 4, the buffer head 6 is connected with a piston 7 which is carried in a flange 8 and projects into the housing 5 of the checking device. A sealing collar 9 forms a tight joint for the piston. There is

3

provided in the housing 5 a cylindrical body 10 having a ball valve 11 at its upper end directly over the collar 9. The cylindrical body 10 has an intermediate conduit 12 which is projected almost to the bottom of the housing 5.

In the example according to Fig. 6, which differs from the example according to Figs. 4 and 5, there are provided further partitions 13 which prevent the liquid from rising in the air space.

Fig. 7 shows a combined inlet and excess pressure valve which is mounted in the housing 5. The excess pressure valve 14 has a conical bore 15 in which is arranged a body 16 working against the action of the internal excess pressure. The body 16 has a conical bore 18 on which a valve member 19 rests, the shank of which is fixed by a nut 20 on the plate 21 and which is under the action of the spring 17.

The method of operation of this valve is clearly seen and requires no fuller explanation.

The method of operation of the embodiment according to Figs. 4 and 5 is briefly as follows:

On the movement of the piston 7 the liquid which is in the cylindrical body 10 is driven out through the throttling conduit 10a. Thus, the speed of the piston 7 is braked according to the size of this conduit. Care, however, must be taken that the brake action is increased in proportion to the speed of the piston 7, in other words, the greater the speed of the abutting shuttle. The braking stroke will consequently be the same at any speed of the shuttle and this will come to a stop at the same position. Any air introduced by the reciprocating movement of the piston 7 into the housing 5 can pass through the valve 11 into the upper space filled with air and consequently does not remain behind the piston and thus cannot affect the working thereof.

Finally, the intermediate conduit 12 ensures that air which is in the upper part of the housing cannot pass into the cylinder filled with liquid.

In the example according to Figs. 8 and 9, in order to avoid the throttling conduit which weakens the construction of the cylindrical body, another solution has been found. Here the piston 7 does not penetrate into a cylindrical body 10 surrounding it on all sides but the cylindrical body 10 embraces the piston 7 with a clearance so that the outflow opening or throttling conduit is formed by the clearance between the piston 7 and cylinder 10. Here, again, there is provided an intermediate conduit 12 in order to prevent the inflow of air into the cylinder.

Otherwise the example according to Figs. 8 and 9 is the same as that according to Figs. 4 and 5.

4

The valve 11 operates with every piston stroke due to the variation of pressure in said clearance; a small quantity of air or the like is pressed through the valve into the air-filled space of the casing; this is constantly replaced by the conveyance of oil out of the bottom of the casing, so that no more air can get into the cylinder body 10.

A further and not hitherto mentioned advantage of the invention resides in that the device is adaptable in a simple manner for all eventual working conditions, in particular for all weights of shuttles. For it is sufficient to vary the throttle conduit according to the examples of Figs. 4 and 5 or the clearance between piston and cylinder in the example according to Figs. 8 and 9 in order to adapt the checking device to a different shuttle weight or to other varied working conditions. In addition, however, there is also the possibility of filling the checking device with liquid of varying viscosity, whereby the same effect is attained. The same shuttle checking device can thus, in fact, be utilized for all working conditions by means of a few standard liquids of known viscosity. The adaptation can also take place not only by the manufacturing firms, but also directly at place of use by inexperienced labour.

I claim:

A shuttle checking device for looms, comprising a casing, a cylindrical body within said casing, a buffer head carried by said casing, a piston engaging said buffer head and adapted to penetrate into said cylindrical body with play between the piston and the cylindrical walls of said body, a sealing collar enclosing said piston and located within said casing, a valve on said cylindrical body substantially above said collar for the withdrawal of air from said cylindrical body, and means forming a conduit connecting the interior of said cylindrical body with the bottom portion of the interior of said casing, whereby air in the interior of said casing is prevented from reaching the interior of said cylindrical body.
